UNITED STATES PATENT OFFICE

ALFRED S. BEARDSLEY, OF MONTEVIDEO, URUGUAY

PADLOCK

Application filed April 9, 1931. Serial No. 528,876.

This invention relates to improvements in padlocks and has for the primary object, the provision of a device of the above stated character which will be free of the disadvantages found in padlocks of the type depending on the use of keys and the operation of proper combinations and which by actual use have been found easily opened by the employment of duplicate and skeleton keys or the employment of wire or the like for picking the locks or the finding of the proper combination after a few attempts.

Another object of this invention is the provision of a lock depending for its operation upon the insertion of a proper slug and the manual operation of a slug receiving and holding means for bringing a certain portion of the slug into engagement with tumblers or shackle catch elements to free the shackle, and due to the location of said means and the tumblers or shackle catch elements, a substantially fool-proof lock is provided and one which may not be easily opened by an unauthorized person.

A further object of this invention is the provision of means for returning the slug receiving and holding means to its initial position when manually released for positioning the slug for easy removal from the lock and at the same time permitting the tumblers or shackle catch elements to automatically assume normal position so that on closing the shackle the latter will be firmly locked.

A still further object of this invention is the provision of a padlock of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings in which:

Figure 1 is a side elevation illustrating a padlock constructed in accordance with my invention.

Figure 2 is a vertical sectional view illustrating the same.

Figure 3 is a transverse sectional view taken on the line 3—3 of Figure 2.

Figure 4 is a side elevation partly in section illustrating the padlock in an unlocked position.

Figure 5 is a plan view illustrating the tumblers or shackle catch elements.

Figure 6 is an edge view illustrating the same.

Figure 7 is an end view illustrating the arrangement of the projections on the tumblers or shackle catch elements that are adapted to be engaged by the slug.

Figure 8 is a plan view illustrating the slug.

Figure 9 is an edge elevation illustrating the same.

Referring in detail to the drawings, the numeral 1 indicates a lock casing which may be of any desired shape and is provided with shackle receiving openings 2 and 3 for receiving the ends of a shackle 4 and one end of the shackle is pivotally mounted within the casing 1 as illustrated at 5 while the opposite end is provided with a notch 6 to be engaged by a plurality of tumblers or shackle catch elements 7. The tumblers 7 are pivotally mounted as shown at 8 and swing between stops 9 and 10 within the casing and are each engaged by a leaf spring 11. The springs 11 are secured in parallelism to the interior of the casing by being positioned between lugs 12. The action of the springs is to normally urge the tumblers 7 against the stop 9 and in a position to engage in the notch 6 of the shackle for holding the latter in a locked position.

Each tumbler is of substantially L-shape with the leg portion 13 carrying at its free end a wedge-shaped projection 14 to engage in the notch 6 of the shackle while the leg portion 15 carries a laterally extending projection or lug 16. The lugs 16 may be of different lengths and shapes to agree with projections 17 formed upon the slug 18 which will be hereinafter more fully described. A shaft 19 is journaled in the side walls of the casing and extends exteriorly thereof and has secured to 100

one end a fingerpiece or knob 20. The shaft 19 has secured thereon a slug receiving and holding member 21 which is apertured to receive one end of a coiled spring 22, the other end of the coiled spring being secured to the casing 1 for the purpose of normally positioning the member 21 to receive the slug 18 by way of the entrance or opening 23 formed in the casing 1. A portion of the member 21 is enlarged and of semi-circular shape so as to expose a portion of the slug 18 when positioned thereon for the purpose of actuating the tumblers 7 when moved thereagainst. The semi-circular portion of the member 21 has formed thereon oppositely disposed lugs 24 and 25 adapted to fit in slots 26 and 27 of the slug 18 for the purpose of retaining the slug on the semi-circular portion and causing the slug to move with the member 21 for actuation of the tumblers 7. It is to be understood that the shapes and sizes of the lugs 24 and 25 may be varied and also the shapes and sizes of the slots 26 and 27 are changed accordingly, thereby providing a large selection or variations to be had in the manufacture of padlocks of this character, and to permit a wider range of slug or variations to be had. The projections 17 on the slug may be made in different sizes and shapes and the projections 16 on the tumblers varied accordingly.

30 A stop 28 is located in the casing 1 for limiting the movement of the member 21 beyond its initial position and opposite the entrance or the opening 23 so that the slug may be easily placed on and removed from the semi-circular shaped portion of the member 21.

35 The slug 18 may be provided with an opening 29 for the purpose of receiving a key ring or the like and if desired the slug may be used for identification purposes by having the name and address of the owner of the lock applied thereto in any suitable manner.

40 A portion of the casing 1 is reduced in thickness to provide a restricted chamber 30 in which the semi-circular portion of the member 21 operates so that the walls of the casing 1 will aid in retaining the slug on the semi-circular portion during the movement of the slug into and out of engagement with the tumblers.

45 In operation, the person having the proper slug inserts the latter through the entrance or opening 23 onto the semi-circular portion with the notches 26 and 27 receiving the projections 24 and 25. The slug so positioned is then moved by rotating the finger piece 20 until the projections 17 engage the lugs 16 and rock the tumblers on their pivots and against the stop 28 freeing the tumblers from the shackle whereby the shackle may be swung into an open position as shown in Figure 4. As soon as the finger piece 20 is manually released, the spring 22 swings the member 21 in engagement with the stop 28 positioning the slug that it may be removed through the

opening or entrance 23 by tilting the lock casing.

When the member 21 and slug return to their initial position as shown in Figure 2, the tumblers 7 automatically return into engagement with the stop 9 by the influence of the springs 11 and into a position that when the notched end of the shackle is inserted into the casing the wedge-shaped ends 14 of the tumblers will engage into the notch 6 and 70 lock the shackle in the casing thereby providing a device which is substantially fool-proof and one that can be easily and conveniently operated when a person is in possession of the proper slug for the respective lock. 75

80 While I have shown and described the preferred embodiment of my invention, it will be understood that minor changes in construction, combination and arrangement of parts may be made without departing from 85 the spirit and scope of the invention, as claimed.

Having thus described my invention, what I claim is:

1. A padlock comprising a casing having 90 an entrance, a pivoted shackle carried by the casing, tumblers in the casing to engage and hold the shackle against pivotal movement, a slug receiving and holding member journaled in the casing, a slug adapted to be positioned on said member by way of the entrance and having slots, lugs on said member fitting in the slots, and a finger piece connected to the member for moving the latter to cause the slug to engage the tumblers to disengage the latter from the shackle. 95

2. A padlock comprising a casing having an entrance, a pivoted shackle carried by the casing, tumblers in the casing to engage and hold the shackle against pivotal movement, 105 a slug receiving and holding member journaled in the casing and having a semi-circular shaped portion positioned in rear of the entrance, lugs on the semi-circular shaped portion, a slug having slots positioned on the 110 semi-circular shaped portion by way of the entrance with the lugs fitting in the slots, and a finger piece for rotating the member to engage the slug with the tumblers to disengage the latter from the shackle. 115

3. A padlock comprising a casing having an entrance, a pivoted shackle carried by the casing, tumblers in the casing to engage and hold the shackle against pivotal movement, a slug receiving and holding member in the 120 casing and having a semi-circular portion, tension means engaging said member to position the semi-circular portion in alignment with the entrance, a slug positioned on the semi-circular portion by way of the entrance and having slots, lugs fitting the slots and carried by the semi-circular portion, projections on said slug, lugs on the tumblers to be engaged by the projections, a finger piece connected to the slug receiving 125 130

and holding member for rotating the latter to engage the projections with the lugs of the tumblers for causing disengagement of said tumblers from the shackle.

5. 4. A padlock comprising a casing having an entrance, a pivoted shackle carried by the casing, substantially L-shaped tumblers pivoted in the casing to engage and hold the shackle against pivotal movement, means for 10 limiting the movement of the tumblers, tension means engaging the tumblers and normally urging them in a position for holding the shackle, laterally extending lugs on the tumblers, a slug receiving and holding member journaled in the casing and having a semi-circularly shaped portion, tension means urging said member into a position for aligning the semi-circularly shaped portion with the entrance, a slug positioned on the semi-circularly shaped portion by way of the entrance, projections on said slug to engage the lugs of the tumblers for disengaging the latter from the shackle when the slug receiving and holding member is rotated, and a finger 25 piece connected to said member.

5. A padlock comprising a casing having portions of opposite walls thereof offset inwardly to form a restricted chamber having an entrance, a movable shackle carried by 30 said casing, tumblers in the casing to engage and hold the shackle against movement relative to the casing, a slug receiving member movably mounted in the restricted chamber of the casing, a slug to be positioned on said member by way of the entrance and movable therewith to engage and free the tumblers from the shackle and retained on said member while out of alignment with the entrance by one of the walls of the restricted chamber, and a finger piece for imparting movement to the slug receiving member.

In testimony whereof I affix my signature.
ALFRED S. BEARDSLEY.
